(57) **CLAIM**

The ornamental design for a beverage bottle with pour spout, as shown and described.

DESCRIPTION

FIG. 1 is a right side elevation view of a beverage bottle with pour spout, showing my new design, and the left side elevation view being a mirror image thereof;

FIG. 2 is a rear elevation view thereof;

FIG. 3 is a front elevation view thereof;

FIG. 4 is a top plan view thereof;

FIG. 5 is a bottom plan view thereof; and,

FIG. 6 is an isometric view thereof.
